(57) **CLAIM**

We claim the ornamental design for a lid for food wrapping box, as shown and described.

DESCRIPTION

The patent or application file contains at least one drawing executed in color. Copies of this patent or patent application publication with color drawing(s) will be provided by the Office upon request and payment of the necessary fee.

FIG. 1 is a perspective view of a lid for food wrapping box of the new design.

FIG. 2 is a front view of the lid for food wrapping box of the new design.

FIG. 3 is a rear view of the lid for food wrapping box of the new design.

FIG. 4 is a left side view of the lid for food wrapping box of the new design.

FIG. 5 is a right side view of the lid for food wrapping box of the new design.

FIG. 6 is a top view of the lid for food wrapping box of the new design.

FIG. 7 is a bottom view of the lid for food wrapping box of the new design; and,

FIG. 8 is an exploded perspective view of the exterior and insert portions of the lid for food wrapping box.

The broken lines shown represent portions of the article that form no part of the claimed design.
